(57) **CLAIM**

The ornamental design for an electric heater, as shown and described.

DESCRIPTION

FIG. 1 is a bottom perspective view of an electric heater in accordance with an embodiment;

FIG. 2 is a bottom view thereof;

FIG. 3 is a first side view thereof;

FIG. 4 is a second side view thereof;

FIG. 5 is a third side view thereof;

FIG. 6 is a fourth side view thereof;

FIG. 7 is a top plan view thereof; and,

FIG. 8 is a top perspective view thereof.

Broken lines represent unclaimed portions of the electric heater and form no part of the claimed design.
